UNITED STATES PATENT OFFICE.

MORRIS WUERPEL, OF ROCHESTER, NEW YORK, ASSIGNOR TO GENERAL RAILWAY SIGNAL COMPANY, OF GATES, NEW YORK, A CORPORATION OF NEW YORK.

POWER RAIL-DRILL.

1,178,567.

Specification of Letters Patent. Patented Apr. 11, 1916.

Application filed November 18, 1913. Serial No. 801,627.

To all whom it may concern:

Be it known that I, MORRIS WUERPEL, a citizen of the United States, and a resident of the city of Rochester, in the county of Monroe and State of New York, have invented a new and useful Power Rail-Drill, of which the following is a specification.

This invention relates to a power rail drill.

10 The primary object of this invention is the production of a power rail drill of such form and construction that it may be readily moved by one man along the line of rails in which it is desired to drill holes.

15 Other objects and advantages will appear as the description of the invention progresses, and the novel features of the invention will be particularly pointed out in the appended claims.

20 In describing the invention in detail, reference is had to the accompanying drawings, wherein I have illustrated a preferred physical embodiment of my invention, and wherein like characters of reference designate corresponding parts throughout the several views, and in which:

Figure 1, is a perspective view of my power rail drill in position upon a rail with the power supplying device, and the support 30 for the main driving shaft and driving shaft removed to more clearly show the parts; Fig. 2, is a side elevation of my power rail drill with certain parts in section to more clearly show the construction; Fig. 3, is a detail of a cam arrangement for manipulating the feeding mechanism for the drill used in my power drill; Fig. 4, is a detail view showing the manner of operating the feed for the drill used in my power drill.

40 Fig. 1, designates a rail, such as the rail of a railway track in which it is desired to bore holes for the purpose of inserting the ends of bond wires so as to render the line of rails electrically continuous at places such as joints, crossings, frogs, and switches.

45 My power drill has a main frame which serves not only to position and support the power mechanism and connections for operating the drill when actually engaged in 50 boring a hole in a rail, but also serves as a means for easily moving the entire mechanism from point to point along the rail upon which work is being performed. This main frame consists of two side rails 3 and 4, each of which has a depending shoulder

as 5, which, when the parts are in a position for drilling a hole in a rail, are positioned firmly against the gage side of the rail. The side rails 3 and 4 are joined at one end by the bar 6, which is extended forwardly 60 of the side rail 4 and bent inwardly so as to be positioned conveniently to form a handle as 7. Fastened securely to the side rail 3 and extending rearwardly thereof are spaced arms 8 and 9 which by means of a 65 shaft 10 support the wheel 2 which has flanges on both sides, which flanges are placed a distance apart sufficient to allow the ball of a rail to rest therebetween and thus form a guide. The rails 3 and 4 at 70 their ends remote from the rail 1, have secured thereto the bearings 11 and 12 which support the square shaft 13. The shaft 13 has the handle 14 secured to one end and this handle is so positioned that it lies a 75 proper distance from the handle 7 so as to serve, together with the handle 7, as what might be termed the two handles of a wheelbarrow, the wheel of which would be 2, so that the operator of the power drill when 80 desiring to move it from place to place would do so by grasping handles 7 and 14 and lifting thereon so as to raise all parts to a convenient position so that he could then easily push the whole device forward 85 or pull it rearwardly, for, as in the ordinary wheelbarrow, the greater portion of the weight would be supported by the wheel 2.

Although the particular means and mechanisms for actually operating the drill 90 during the process of boring the rail form no part of applicant's invention, nevertheless, an acceptable form of such means has been herein shown so as to more fully show the connection between the handle 14 and 95 the means for actually drilling the rail, as in applicant's device one phase of the invention resides in the fact that one of the handles which serves as a means for assisting in moving the entire mechanism, also 100 serves as a means for quickly withdrawing the drill from operative position and also to quickly place the drill approximately in operative position.

The means for supplying power may be 105 any of the ordinary and well known means suitable for the purpose and applicant has herein shown an internal combustion engine 15, as an example of such means. As applicant has shown an internal combustion en- 110

gine 15, and as such engines generally require to be manually started, a means for starting such engine is also shown which consists of a crank 25 attached to shaft 26 which is movable longitudinally in the bearing 27 and which bears at its inner end half of a clutch member 28 which is adapted to engage with half clutch member 29 attached rigidly to shaft 18 when the shaft 26 is moved longitudinally to the left as viewed in Fig. 2, so that by a movement thereafter of the crank 25 in a clockwise direction the shaft 18 and gear wheel 17 and 16 are caused to turn so as to actuate the internal mechanism of the internal combustion engine 15 and so give it an initial movement necessary to cause it to start. This power means is connected to the drill by means of gear 16, which meshes with gear 17, rigidly fastened to shaft 18. The shaft 18 is journaled in the bearings 19 and 20 and bears driving pulley 21, which, by suitable means as a belt 22 drives a pulley 23, which is rigidly attached to drill spindle 24. The drill spindle 24 is supported by a bearing 30 and by the long sleeve 31, and has a drill as 32 properly secured in one end and is spring pressed in one direction by the spring 33 bearing at one end against the bearing 30 and at the other end against the head 34 attached to the outer end of the spindle 24.

In order to cause the drill to feed forward when in operation, sleeve 31 has teeth 35 cut in its upper surface and is mounted so as to move freely longitudinally in the bearing 36 formed in the cross piece 37. The teeth 35 are engaged by pinion 38 on a shaft 39, which shaft also carries a worm wheel 40 which meshes with a worm 41. This worm 41 has on one end the pulley 42 which is driven by means of belt 43 from the pulley 44 attached to shaft 18, so that a rotation of shaft 18 causes a rotation of worm 41, worm wheel 40, shaft 39, and gear wheel 38, and, consequently, a forward movement of sleeve 31, which, abutting against the shoulder 45 of drill spindle 24, causes the drill spindle to move toward the rail, thereby causing the drill 32 to be advanced as the drilling progresses.

In order to provide for a rapid movement in either direction of the drill spindle 24, means have been provided to disengage the worm 41 from the worm wheel 40 so that the drill spindle together with the drill may be moved in one direction rapidly by the spring 33 or may be moved in the other direction by manually pushing against the member 34. This means for disengaging worm 41, consists of the members 46 and 47 in which the worm is journaled eccentrically so that a rotation of the members 46 and 47 in one direction causes worm 41 to be raised from engagement with worm wheel 40 and a movement of the members 46 and 47 in an-

other direction causes an engagement of worm 41 with worm wheel 40. The means for moving the members 46 and 47 is the handle 48 which is attached to a bar 49 having spaced ends 50 and 51 extending at right angles to it. Pins 52 secure the members 46 and 47 and the ends 51 and 50 together respectively so that a movement up or down of the handle 48 causes the members 46 and 47 to turn upon themselves and so raise or lower the worm 41.

The drill spindle 24, the sleeve 31, and the feeding mechanism including the worm 41, having the pulley 42, are journaled in and supported by cross pieces 37 and 53 which cross pieces form with members 54, 55 and 56 and 57 a carriage held between the side rails 3 and 4 and slideable thereon. The carriage is moved bodily with all of its supported parts by means of links 58 which at one end are connected to the carriage and to the other end are connected with the crank arms 59, so that a movement of the shaft 13 by means of handle 14 causes a movement of the carriage upon which the drill spindle 24, sleeve 31 and the feed mechanism are supported.

In order that the drill shall be brought to the proper position in relation to the rail and in order that the carriage supporting the feed mechanism shall be held from movement during the operation of drilling, applicant has provided a wedging device which is intended to be forced tightly between the under side of the ball of the rail and the top side of the flange of the rail. This wedging device consists of the upper and lower beveled members 60, each pivoted by pins 61 to arm 62 which is rigidly fastened by means of member 64 to the carriage. The distance between the members 60 may be varied by means of the right and left hand threaded member 63 so as to provide for the variations in different rails.

The handle 14 when moved to the position in which it should be placed for drilling, is supported by the bracket 65 which is so placed that the shaft 13 is revolved to a position such that the line of action through the pins in the ends of the links 58 passes through the center of the shaft 13 and at the same time beveled members 60 are pressed firmly against the surface with which they should contact, so that the carriage carrying the feed mechanism for the drill is held perfectly rigid.

As is well known to those skilled in the railway art all devices for use upon the rails of an operating railway which in use project over or upon the ball of the rail, must be of such a nature that they can be removed with the greatest of rapidity, because at any moment a train is liable to approach at an extremely high speed affording in some cases an almost infinitesimal amount

of time in which to remove any obstruction from the top surface of the ball of the rail.

Applicant has provided in this power drilling means for quickly removing the device from a position in which it will be an obstruction to the movement of trains over the rail. This is provided for by causing the handle 14 which, as was hereinbefore explained, acts as one handle when the device is pushed along similarly to a wheelbarrow, to also form a means for quickly retracting the drill and the beveled wedging member 60, so that the shoulders 5 may be freed from the gage side of the rail and the whole device, if necessary, overturned in a direction away from the rail, using the wheel 2 as a pivot. The virtue of employing handle 14 both for transporting the power drill as a whole and also for quickly freeing the device from the rail, will be readily seen when it is realized that the natural position for one operating the drill would be in front of the same with one hand grasping the handle 7 and the other hand grasping the handle 14 so as to be in a position to quickly retract the drill when the hole in the rail has been completely bored and to move on to the next position for drilling. Furthermore, an alert operator would, during the drilling operation, always have his hand upon the handle 14 so as to quickly withdraw the drill from its hole if any unforeseen difficulty is experienced in drilling. In short, the ordinary operation of the power drill causes the operator to be in proper position and to have hold of the proper parts so as to instantly disengage the device from the rail and remove it from the rail.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. In a rail drill: a drill; a carriage for supporting the drill; side bars included in a framework for supporting the carriage; said carriage bearing a wedge member adapted to fit against one side of an object to be drilled and said side bars having shoulder pieces secured thereto adapted to fit against the opposite side of the said object; a wheel adapted to rest on the object and secured to the side bars; a handle secured to the side bars; a member supported by the side bars and connected to the carriage for causing the carriage to move toward and away from the said object and so causing the said object to be clamped between or freed from the shoulder pieces and the wedge; and

means for operating the drill; said member also serving as a means together with the handle by which the complete mechanism may be transported partly supported by the wheel.

70

2. In a rail drill: a drill; a support for the drill; means including a movable handle for clamping said support tightly to a rail; a second handle and a wheel secured to said support whereby the support may be moved bodily supported partly by the wheel by lifting on and then pushing or pulling the two handles; and means for operating the drill.

3. In a rail drill: a drill; a support for the drill, said support having shoulder pieces for engaging one side of a rail and a wedge member for engaging the opposite side of the same rail; means carried by the support for driving the drill and feeding the same forward; a wheel secured to the support and adapted to rest on the rail; a handle secured to the support; a member adapted to serve as a handle for propelling the support partly supported by the wheel and for disengaging the drill and wedge from in contact with the rail; and means for operating the drill.

4. In a rail drill: a drill; a support for the drill, said support having shoulder pieces for engaging one side of a rail and a wedge member for engaging the opposite side of the same rail; a wheel secured to the support and adapted to rest on the rail; a handle secured to the support; a member adapted to serve as a handle for propelling the support partly supported by the wheel and for disengaging the drill and wedge from in contact with the rail; and means for operating the drill.

95

5. In a rail drill, in combination: a drilling mechanism; a drill included in said mechanism; a motor included in said mechanism for causing the drill to turn; means operated by the motor for automatically feeding the drill forward; a carriage supporting said mechanism; a supporting frame arranged for the carriage to move upon; means connected to the frame for adjusting the position of the carriage and means connected to the carriage for adjusting the position of the drill.

100

6. In a rail drill, in combination: a drilling mechanism; a drill included in the said mechanism; a motor included in said mechanism for causing the drill to turn; means operated by the motor for automatically feeding the drill forward; means for disconnecting the said feeding means from the drill; a carriage supporting said mechanism; a supporting frame arranged for the carriage to move upon; means connected to the frame for adjusting the position of the carriage and means connected to the carriage for adjusting the position of the drill.

115

120

125

130

7. In a rail drill, in combination: a drilling mechanism; a drill included in the said mechanism; a motor included in said mechanism for causing the drill to turn; means for automatically feeding the drill forward; means for disconnecting the said feeding means from the drill; a carriage supporting said mechanism; a supporting frame arranged for the carriage to move upon; 5 means connected to the carriage for adjusting the position of the drill; a handle connected to the frame; a wheel connected to the frame and a device connected to the frame for adjusting the position of the carriage and arranged so that when the carriage is moved away from the object drilled the device will assume a position whereby it may be used as a handle together with the first said handle for lifting the rail drill and for transporting it partly supported on the said wheel.
- 10 8. In a rail drill, in combination: a drilling mechanism; a drill included in said mechanism; a motor included in said mechanism for causing the drill to turn; means for automatically feeding the drill forward; means for disconnecting the said feeding means from the drill; a carriage supporting said mechanism; a supporting frame arranged for the carriage to move upon; 15 means connected to the carriage for adjusting the position of the drill; clamping mem- 20 bers attached to the frame; clamping members attached to the carriage coacting with the clamping members attached to the frame 35 for clamping firmly to the object to be drilled when the carriage is moved toward the said object; a handle connected to the frame; a wheel connected to the frame and a device connected to the frame for adjusting the position of the carriage and arranged so that when the carriage is moved away from the said object the device will assume a position whereby it may be used as a handle together with the first said handle for 40 lifting the rail drill and for transporting it partly supported on the said wheel.
- 15 9. In a rail drill, in combination: a drilling mechanism; a drill included in said mechanism; a frame supporting said mech- 20 anism; a wheel connected to the frame and adapted to roll upon an object to be drilled; a handle connected to the frame and a device connected to the frame for removing the drill from the object being drilled, said 25 device thereafter serving as a handle together with the first said handle for lifting the rail drill and for transporting it partly supported by the wheel.
